Primary Examiner—Melanie Tung

Assistant Examiner—Susan Moon Lee

(74) Attorney, Agent, or Firm—Rader, Fishman & Grauer, PLLC

(57) **CLAIM**

The ornamental design for a chip, as shown and described.

DESCRIPTION

FIG. 1 is a perspective view of a new chip design;

FIG. 2 is a top plan view thereof;

FIG. 3 is a left side elevation view thereof;

FIG. 4 is a right side elevation view thereof;

FIG. 5 is a front elevational view thereof;

FIG. 6 is a rear elevational view thereof; and,

FIG. 7 is a bottom plan view thereof.
